US0D1050045S

(12) **United States Design Patent** (10) **Patent No.:** **US D1,050,045 S**
Du (45) **Date of Patent:** **** Nov. 5, 2024**

(54) **SURGE PROTECTOR**

(71) Applicant: **Guangzhou Kerui Innovation Tech. Co., Limited**, Guangzhou (CN)

(72) Inventor: **Zhanyan Du**, Guangzhou (CN)

(73) Assignee: **Guangzhou Kerui Innovation Tech. Co., Limited**

(**) Term: **15 Years**

(21) Appl. No.: **35/519,659**

(22) Filed: **Nov. 29, 2023**

(80) **Hague Agreement Data**

Int. Filing Date: **Nov. 29, 2023**

Int. Reg. No.: **DM/234215**

Int. Reg. Date: **Nov. 29, 2023**

Int. Reg. Pub. Date: **Jan. 12, 2024**

(57)

CLAIM

The ornamental design for a surge protector as shown and described.

DESCRIPTION

1.1 : Perspective

1.2 : Perspective

1.3 : Front

1.4 : Back

1.5 : Left

1.6 : Right

(Continued)

1.7 : Top

1.8 : Bottom

The broken lines shown in the drawings illustrate portions of the surge protector that form no part of the claimed design.

1 Claim, 8 Drawing Sheets
